(57) **CLAIM**

The ornamental design for a surgical instrument for hypertension pneumothorax, as shown and described.

DESCRIPTION

FIG. 1 is a perspective view of a surgical instrument for hypertension pneumothorax showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is top plan view thereof; and,

FIG. 7 is a bottom plan view thereof.

The broken lines showing of rings is for the purpose of illustrating portions of the surgical instrument for hypertension pneumothorax and forms no part of the claimed design.
